(57) **CLAIM**

The ornamental design for a display screen or portion thereof with animated graphical user interface for stock trade, as shown and described.

DESCRIPTION

FIG. 1 is a front view of a display screen or portion thereof with animated graphical user interface for stock trade showing a first image in the sequence showing our new design; FIG. 2 is a second image thereof; FIG. 3 is a third image thereof; FIG. 4 is a fourth image thereof; FIG. 5 is a fifth image thereof; and, FIG. 6 is a sixth image thereof.

The long dash-short dash broken lines showing the display screen or portion thereof form no part of the claimed design. All other broken line, except for the short-dashed lines within the circular icons shown in FIG. 5, and text shown in white strikethrough illustrate portions of the graphical user interface that form no part of the claimed design.

The appearance of the animated images transitions between the images shown in FIGS. 1-6. The process or period in which one image transitions to another forms no part of the claimed design.
